Attorney

UNITED STATES PATENT OFFICE.

LAURA HILL, OF SEATTLE, WASHINGTON.

LIFEBOAT.

Application filed June 22, 1926. Serial No. 117,669.

The invention is a life boat which is provided with pontoons for preventing its capsizing and to assist persons in the water climbing into the boat, and foldable beams 5 for holding the boat away from a larger boat.

The object of the invention is to provide a life boat that will stay afloat regardless of the weather or conditions.

10 Another object of the invention is to provide a life boat having means by which persons in the water may readily climb into the boat.

15 A further object of the invention is to provide a life boat having separate storage compartments.

20 And a still further object of the invention is to provide a safe and efficient life boat, which is of a simple and economical construction.

25 With these ends in view, the invention embodies a boat having air compartments in it and attached to it, storage compartments in it, a lamp, foldable pontoons, and foldable beams for holding it away from a larger boat.

30 Other features and advantages of the invention will appear from the following description, taken in connection with the drawings, wherein:—

Figure 1 is a side elevation.

Figure 2 is a longitudinal section.

Figure 3 is a cross section through the center of the boat.

35 In the drawings the boat is shown as it would be made wherein numeral 1 indicates the body of the boat, numeral 2 the pontoons and numeral 3 the foldable beams.

40 The body of the boat may be of any suitable type or made in any suitable manner. In the design shown in Figure 2, the body of the boat is hollow as indicated by the numeral 4, whereas in the design shown in

45 Figure 3, the boat is solid. It is therefore understood that the boat may be made of any suitable material and provided with a sealed air compartment in its shell, or it may be made of any suitable material that will float.

50 The boat may be provided with a rudder 5 at the rear, which may be of any suitable design, and arranged in any suitable manner. At the bottom of the boat are triangular shaped pontoons 6 and 7 as shown, which provide additional buoyancy

55 for the boat. The forward end of the boat may be provided with a storage compart-

ment 8 which has a hinged cover 9 and at the stern is another similar compartment 10, which may also have a hinged cover as indicated by the numeral 11. The body of the 60 boat may also be provided with a lamp 12 which may be located in any suitable position and lighted by any suitable means.

At the sides of the boat are vertical members 13 and 14 to which the pontoons 2 are 65 connected by hinges 15 and at the upper ends of the pontoons are connections 16 by which the pontoons are connected to bars 17 and 18. The bars 17 and 18 are pivotally attached and the outer end of the bar 18 is 70 provided with an opening 19 through which it may be held to a clip 20 adjacent the upper ends of the members 13 and 14. At the inner end of the member 17 is a hook 21 that may be placed through an eye 22 to hold the 75 pontoon in the upward position. It will be observed that when this hook is released the pontoon may be lowered and when the bars 17 and 18 are straightened as shown in Figure 3, the upper end of the bar 18 may be 80 held by a pin to the clip 20, and the pontoon will be held in a horizontal position.

85 At the center of the boat are foldable beams 3 which are formed with a rigid straight member 21 and a foldable member 22 that may be opened to an outstanding position as shown at one side of the boat in Figure 3. When not in use these beams will be folded to the closed position. When open they will hold the boat away from a larger 90 boat.

The boat may be provided with any other suitable equipment such as seats 23 and oar locks 24.

95 It will be understood that changes may be made in the construction without departing from the spirit of the invention. One of which changes may be in the design, position or arrangement of the pontoons, another may be in the design or arrangement 100 of the folding beams, and still another may be in the use of other means for holding the pontoons in either position.

The construction will be readily understood from the foregoing description. To 105 use the device, it may be assembled as shown, and it will be observed that the pontoons may readily be lowered or the beams 3 opened when it is desired to use them to hold the boat away from a larger boat. It 110 will also be observed that the particular arrangement of air compartments will keep

the boat well out of the water so that it will be practically impossible to sink it.

Having thus fully described the invention, what I claim as new and desire to secure by 5 Letters Patent, is—

In a life boat of the class described, a boat in which a sealed air compartment is formed in a shell and additional air compartments formed in beams below the ends 10 of the said boat, pontoons hinged to the sides

of the said boat, means for holding the said pontoons in an upright position against the sides of the boat, other means for holding the pontoons in an extended position, and a plurality of transverse beams hinged to the 15 upper edges of the said boat and adaptable to be folded in across the center of the boat and also to extend outward.

In testimony whereof I affix my signature.
LAURA HILL.
